UNITED STATES PATENT OFFICE

104,202

DESIGN FOR A DISPLAY PANEL FOR COLOR COMBINATIONS

Carleton B. Spencer, Royal Oak, Mich., assignor to Ditzler Color Company, a corporation of Michigan

Application December 5, 1936, Serial No. 66,335

Term of patent 14 years

To all whom it may concern:

Be it known that I, Carleton B. Spencer, a citizen of the United States, residing at Royal Oak, in the county of Oakland and State of Michigan, have invented a new, original, and ornamental Design for a Display Panel for Color Combinations, of which the following is a specification, reference being had to the accompanying drawing, forming a part thereof.

The figure is a plan view of a display panel showing my design, which is characterized in that a substantial portion is covered with a coating A, of one color, while the remainder of the panel is covered with a coating B of a congruous color, the two distinct sections being separated by an arcuate line of demarcation C. A line D,

of color in contrast to the base color A, is superimposed thereon and extends transversely of the panel adjacent the upper edge thereof. A plurality of lines E, of less width and of a second contrasting color, border said line D. A disc F of one of the contrasting colors utilized in the lines D and E, is superimposed centrally of the base color section B. A second disc G, of the second contrasting color utilized in the lines D and E is positioned upon said disc F. The panel is of a thickness approximating that of heavy cardboard.

I claim:

The ornamental design for a display panel for color combinations, as shown and described.

CARLETON B. SPENCER.
